BEVERAGE ADVERTISING SIGN OR THE LIKE

Amber L. Cochran, 1019 Quinientos,
Santa Barbara, Calif.

Filed Oct. 27, 1960, Ser. No. 62,641

Term of patent 14 years

(Cl. D1—12)

FIG. 1 is a side elevational view of a beverage advertising sign showing my new design;

FIG. 2 is a top plan view thereof;

FIG. 3 is a rear elevational view thereof; and

FIG. 4 is a front elevational view thereof.

The broken-line representations of the word "cola" in FIGS. 1 and 2 are for purpose of illustration only.

I claim:

The ornamental design for a beverage advertising sign or the like, substantially as shown and described.
